(57) **CLAIM**

The ornamental design for a mosquito killer light, as shown and described.

DESCRIPTION

FIG. 1 is a front, right and top perspective view of a mosquito killer light, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the mosquito killer light that form no part of the claimed design.
